FUEL OIL BURNER

Filed June 30, 1921

UNITED STATES PATENT OFFICE.

EUGENE JOHN MOYNIHAN, OF SPRINGFIELD, MASSACHUSETTS.

FUEL-OIL BURNER.

Application filed June 30, 1921. Serial No. 481,572.

To all whom it may concern:

Be it known that EUGENE J. MOYNIHAN, a citizen of the United States, residing at Springfield, in the county of Hampden and State of Massachusetts, has invented certain new and useful Improvements in Fuel-Oil Burners, of which the following is a specification, reference being had to the accompanying drawing.

10 This invention refers to oil burners and more particularly adapted for the combustion of fuel oil. The invention has among its objects:

15 To provide a burner permitting a relatively free and effective flow to the oil.

To provide in such a burner an arrangement whereby the propelling force will be transmitted directly to the oil in the combustion chamber.

20 To provide an arrangement for atomizing the oil effectively.

To provide means for supplying air alone; steam alone, or a combination of both as the condition may make desirable.

25 To provide an arrangement for adjusting the wearing parts, or for their inspection or their repair or removal.

To provide the device with orifices for the fluid that will permit the most effective flow and use of the oil.

30 And many other objects which will become apparent as the invention is more fully set forth.

In the past art, many practical difficulties have been experienced in the use of fuel oil devices, in that they "stick" or do not provide for a proper burning of the oil. In the latter case, the oil will frequently blow right through the burner without being caught by the flame and burnt effectively, thereby causing a great loss of thermal efficiency in the use of the oil. Most burners are such that they cannot be cleaned and inspected or repaired, which

45 renders them more or less inconvenient to use. They also employ the principle of applying the pressure behind the fluid and as a part of the stream as the oil comes through the nozzle. In this invention, the air or steam pressure is applied after the liquid fuel leaves the nozzle, mixes with it, and sprays it in a very atomized state through the mouth of the burner, which

is enlarged on purpose to give a more effective action. The manner of flowing the oil through the nozzle is such, that the oil is giving a twirling or displaced movement when it leaves the nozzle, and the air or steam is impressed behind the flow of oil in the nozzle and at a direction that assists in breaking it up without interfering with the proper flow out of the burner mouth. The flow is such that the spitting of the burner is positively prevented.

In the drawings which illustrate by way of example an embodiment of this invention,

Figure 1 is a side view of a burner embodying this invention.

Figure 2 is a longitudinal section through the burner.

Figure 3 is a plan view of the burner.

Figure 4 is a rear view of the burner.

Figure 5 is a detail of the nozzle used in this invention.

Figure 6 is a modified form of nozzle.

Figure 7 is another modified form of nozzle.

Similar reference characters refer to similar parts throughout the drawings.

In the construction shown 1 represents a fuel pipe, attached to a burner 2 adapted for fuel oil burning. The burner has a rear chamber 3, provided with a threaded orifice 4 arranged to receive pipe 1, at its rear end. The chamber is bell shaped, preferably as shown in the drawings, and has its other end threaded interiorly to engage over a nozzle body 5. The nozzle body is threaded at ends 7 and in the middle provided with a hexagon or tool engaging portion 8, which also forms a stop for the threading movement of the chamber member and also of the mouthpiece 9 that threads thereon and swells out from the body as shown in the drawings.

The nozzle body has a cone shaped seat 10 provided in the end facing the mouthpiece, a small chamber space 11 extending from the seat portion and below that there is an orifice 12 to permit an adjusting screw 13 to project through. Several passages 14, angularly arranged point inwardly from the bottom of the nozzle body to and into the chamber space 11. A nozzle 24 of inverted cone-shaped form rests on the seat in the

body and is held thereon by means of a nut 16 that is threaded on the adjusting screw 13. The nozzle is provided with a plurality of spiral grooves 17 that begin from the 5 nozzle end pointed in the chamber space 11 and terminate on the exterior face 18 that is in the mouthpiece, and adjacent to the bottom thereof.

The mouthpiece is provided with a plurality of holes 19 which are arranged to 10 permit the insertion of air, steam or other fluid piping; and the portion of the mouthpiece for same is arranged so as to make the piping direct at an angle across the 15 portion in front of the nozzle and towards the sides of the mouthpiece.

In the modifications of the nozzle that of Figure 6 is provided with passages 20 through the nozzle that are relatively straight and do not terminate on the periphery of the same. In Figure 7 the general surface spiral is used except that a short distance below the top surface of the nozzle, the latter is pierced so as to permit 25 the orifices of the passages to appear a slight distance in from the periphery.

The operation of the devices is as follows. The oil is flowed into the rear chamber 3 and fills its space. It then flows through 30 the passages 14 to the chamber space 11 when it strikes the adjusting screw and flows up into the grooves, thence being spirally whirled until it reaches the face of the nozzle in the mouthpiece at the bottom thereof. The fluid comes out of the nozzle with 35 a twisting movement which tends to break the adhesion of its particles, which are then caught by the air flowing through the holes 19, and thrown angularly through the enlarged mouthpiece which causes further 40 splitting up by reason the meeting of particles with one another and against the sides of the mouthpiece. The sides of the mouthpiece also restrain the fluid from being lost 45 or misdirected. The position of the nozzle with respect to the open end of the mouthpiece is about the same as the length of the cone nozzle. The adjustment of the nozzle permits the nozzle to be placed in 50 a more effective position should it be required, due to a variation of oils or fuels.

The face of the modified form shown in Figure 7 is concaved as indicated. The position of the air or steam supply is such 55 as to direct at the fuel orifices in the nozzle and not only that the fuel may be caught as it comes out but also in a self-cleaning manner. The mouthpiece is susceptible to adjustment so that its open end may be 60 made most suitable with respect to any general action of the fuel therein with respect to its open end.

While there are several forms of the inventions indicated in the drawings, it is 65 not intended or desired to limit this appli-

cation to the particular construction shown, nor in any other way, otherwise than limited prior art, as it is well understood that many modifications could be made using the same principles as this invention and coming 70 within the scope of the appended claims.

Having thus described the invention, what is claimed is:

1. A fuel oil burner comprising in combination, a bell shaped mouthpiece having 75 an open restricted bottom, a cone shaped nozzle having a plurality of spiral grooves on its peripheral surface, said grooves terminating in the base surface of the nozzle, a rear chamber member, and a union member 80 for receiving the nozzle and adjustably attaching the rear chamber member and the mouthpiece together, and means for adjusting the nozzle in the union member.

2. A fuel oil burner comprising in combination, a bell shaped mouthpiece having an open restricted bottom, a cone shaped nozzle having a plurality of spaced spiral grooves on its peripheral surface, said 85 grooves winding from the smaller end of the nozzle to the widened base end, and emerging through the base end of the cone nozzle, a rear chamber member adapted to receive the fuel oil connections, a union member having a cone like recess to receive 90 the nozzle with its widened base portion facing outwardly, and with a relatively small chamber in rear of its restricted end and with a plurality of spaced passages entering 95 from the rear chamber member into the small chamber aforesaid, and means for adjusting the cone nozzle into the cone recess into closer or looser contact with each other, said union member being arranged 100 to receive and hold the rear chamber member and the open restricted bottom of the mouthpiece, and means in the mouthpiece for the insertion of air or steam into the mouthpiece and into the fuel oil coming 105 through the grooves in the nozzle.

3. A fuel oil burner comprising in combination a bell shaped mouthpiece having a plurality of spaced air or steam orifices at its restricted end portion, said restricted portion being provided with an open threaded portion, a union member adjustably attached to the open threaded portion of the mouthpiece having an enlarged middle portion extending beyond the bottom of the mouthpiece, said member having an interior 110 passage therethrough and a plurality of converging passages directed into the rear portion of the interior passage in the member, a nozzle having a plurality of spiral grooves beginning at the portion of the 115 nozzle adjacent the converging passages and terminating at the surface of the nozzle within the mouthpiece and in rear thereof, and in the base of the air or steam orifices, and an adjusting screw on the end of the 120 nozzle.

125

130

nozzle for adjusting the nozzle within the interior passage and controlling the fuel to the grooves and their terminations in the mouthpiece, and a rear chamber member adjustably attachable to union member and adapted to provide a reservoird supply of fuel to the nozzle.

In testimony whereof I hereunto affix my signature in the presence of two witnesses.

EUGENE JOHN MOYNIHAN.
